US00D762536S

(12) **United States Design Patent**
Wurzer et al.

(10) **Patent No.:** **US D762,536 S**
(45) **Date of Patent:** **** Aug. 2, 2016**

(54) **CLUTCH EXTENDER**

(71) Applicants: **David T. Wurzer**, Carroll, IA (US);
Adam J. Wurzer, Carroll, IA (US);
Terry D. Wurzer, Panora, IA (US)

(72) Inventors: **David T. Wurzer**, Carroll, IA (US);
Adam J. Wurzer, Carroll, IA (US);
Terry D. Wurzer, Panora, IA (US)

(**) Term: **14 Years**

(21) Appl. No.: **29/524,184**

(22) Filed: **Apr. 17, 2015**

(51) LOC (10) Cl. **12-11**
